UNITED STATES PATENT OFFICE

HARRY McADAMS, OF ATLANTIC CITY, NEW JERSEY

TERRY LOOP FABRIC KNITTING MACHINE

Application filed December 31, 1929. Serial No. 417,712.

The invention relates to improvements in knitting machines particularly well adapted for the knitting of terry loop fabrics.

The primary object of this invention is the provision of an improved knitting machine and associated apparatus, which is adapted to economically knit terry loop fabric consisting of a base knitted web having relatively long and prominently projecting terry loops on both sides thereof; the improvement consisting in means to practically knit and arrange the terry yarn or yarns in the base knitted web in such manner that while providing relatively long and prominently projecting terry loops, yet the terry looping yarn will be fastened in an efficient and durable relationship upon the base knitted web, to prevent the unraveling thereof during use. With prior terry loop knitted fabrics, adapted more particularly for washrags, toweling, and the like, it was found to be a relatively difficult procedure to affix the terry loop knitting yarns to the base fabric, so as to prevent the unraveling thereof during use, and at the same time provide relatively long and prominently projecting terry loops in the finished product. This fact, combined with the fact that for a high quality product it is necessary to knit the base yarn stitches so close together and project the terry loops therethrough so close together that the base yarn will be entirely hidden in the finished product, has caused manufacturers to expend enormous sums of money in an endeavor to perfect a quality product. This invention comprehends the provision of mechanism which will enable the efficient and economical production of such type of fabric wherein the terry looping yarns are locked by stitching with the base knitted web, so as to prevent the unraveling thereof, without sacrificing lengths in the terry loops.

A further object of this invention consists in the provision of improved means to enable the practical manufacture of terry loop knitted fabric, with the loops projected on both sides of a single base knitted web,

with all of the yarn introducing wheels arranged at one side of the needle line.

A further object of this invention is the provision of improved means to expedite and facilitate the support of relatively long projected terry looping yarns upon the needles of a knitting machine or cylinder, prior to or during the introduction thereof to the fabric.

A further object of this invention is the provision of an improved terry loop knitted fabric.

Other objects and advantages of this invention will be apparent during the course of the following detailed description.

In the accompanying drawings, forming a part of this specification, and wherein similar reference characters designate corresponding parts throughout the several views,

Figure 1 is a plan view of the knitting machine, showing more particularly the arrangement of the yarn and fabric cooperating burs and parts with respect to the needle arrangement upon the cylinder.

Figures 2 and 3 are views, on a developed plane, showing details for effecting the knitting of a base fabric and the introduction of a terry looping yarn for substantially one-half of the knitting operation, that is, the substantial completion of the knitting of so much of the base knitted web and cooperation therewith of the terry looping yarn as is necessary to introduce the terry looping yarn upon the outer or external side of the fabric, as positioned upon the machine.

Figures 4 and 5 are views showing parts successively operating upon the fabric, in a developed plane, showing the apparatus for the knitting of terry loop fabric, for the introducing, knitting, and looping of a second knitting yarn and a second terry yarn, for the production of loops upon the inner side of the fabric, as positioned upon the machine.

Figure 6 is a fragmentary sectional view taken on a vertical plane through a terry loop introducing wheel, showing the sinkers thereof cooperating with the needles of the cylinder of the machine, the view being taken

substantially on the line 6—6 of Figure 1.

Figure 7 is a fragmentary view partly in section, showing the sinker arrangement of the terry loop forming wheel in its looping relation with the needles of the knitting machine cylinder.

Figures 8, 9, 10 and 11 are respectively cross sectional views taken on their respective lines in Figures 2, 3 and 5 of the drawings.

Figures 12, 13 and 14 are views showing the blade arrangement of certain yarn co-operating wheels and burrs, the bladed arrangement being diagrammatically shown in developed planes.

Figure 15 is an enlarged, distorted, and rather diagrammatic representation of the relation of the knitting yarns forming the stitched loops of the plain base knitting, with respect to a pair of terry looping yarns, and with respect to a weft yarn.

Figure 16 is a sectional view taken through one of the wales of the base knitted web, showing an enlarged, but substantially accurate relation, as to relative size, of the knitting and terry loop forming yarns, and their relative association.

The improved knitting machine must be considered in connection with my co-pending applications Serial No. 148,849, filed November 17, 1926, Patent No. 1,800,092, and Serial No. 208,483, filed July 26, 1927, Patent No. 1,805,339. The machine of the present invention is substantially identical with the machines of those applications, except insofar as the arrangement of knitting, and fabric introducing, and providing wheels, burrs, and parts are concerned. The letter A may generally designate the improved knitting machine, which may include a supporting bed or frame B, having a rotary cylinder construction C thereon operatively driven in any approved manner (not shown), such as shown in my above identified application, or otherwise, about a shaft D as an axis. Any approved fabric take-up mechanism (not shown) may be provided, adapted to cooperate with the needles of the cylinder C in the upward support of the fabric. This is a conventional feature which need not be illustrated or described. A modified and improved type of loop introducing wheel F is provided for introducing the loops of a terry yarn upon the needles for looping at the outer side of the fabric, and a similar terry yarn looping wheel G is provided for introducing a terry looping yarn upon the needles in an arrangement which enables the loops to be introduced at the inner side of the fabric, in the finished product as it comes to the take-up mechanism.

As is well known, the supporting bed B is horizontally positioned and is provided with an annular flange 25 for guiding rotation of the cylinder C. The latter includes

the top wall 26 which is integrally connected to the depending cylinder body 27. On the outer side of the cylinder body 27 the needle plates or segments 30 are arranged in usual relation, being held by detachable bolts 31, as more particularly shown in Figure 6 of the drawings, and the needles 32 are clamped in position upon the cylinder body by the plates or the segments 30, in well known relation. The needles are of the spring beard type, although they may be of any suitable type. In this type of machine the needles rotate with the cylinder C, and are non-reciprocable. The cylinder is of considerable diameter, so as to permit the knitting of fabric of considerable width in the piece. The needles are very closely spaced, so as to enable the knitting of stitches or loops in the base knitting fabric, quite closely together. This complicates the practical production of quality type of terry loop knitted fabric. In the present invention but one series or set of the terry yarn, waft yarn, and stitch yarn controlling wheels, burrs, and devices have been shown, and it is to be understood that any number of these sets or series may be provided, as desired, consistent with the size of the fabric knitted upon the machine, that it, the diameter thereof and the speed with which the fabric is produced.

Within the circular line of knitting needles 32 is provided a grooved top plate 41, which is held stationary in the usual manner provided for such machines, as by being secured to an upstanding sleeve shown at 40 in Figure 1 of the drawings, about the shaft D. This grooved top plate supports brackets or standards which in turn support certain knitting and yarn controlling wheels, burrs, and details to be subsequently described. On the bed B, externally and concentrically about the needle cylinder C, is provided the conventional grooved back stand ring 45, shown in plan in Figure 1 and in cross section in Figure 6, which receives suitable stands or supports for the mounting of various burrs, bladed wheels, terry yarn looping wheels, and other details, as will be subsequently mentioned.

Prior to a description of the arrangement of knitting wheels, burrs, and details which control the yarns upon the machine it is thought best to describe the arrangement of the knitting, terry loop providing and weft yarns in the finished fabric K, which has been shown enlarged and rather distorted in Figures 15 and 16.

Referring first to the knitting of the base web, which has been designated generically by reference letter H, the same is formed of knitting threads or yarns 50 and 51, which knit alternate courses in the fabric, according to the arrangement which has been given in these numerals in Figure 15 of the draw-

ings. The knitting is the usual type of stocking knitting, with the knitted stitch loops arranged in wales. Thus the knitting yarns 50 in alternate horizontal courses provide the knit or stitch loops 52, which are of course inter-knitted with the knit loops or stitch loops 54 of the knitting yarn 51 in the remaining horizontal courses, as well shown in various views of the drawings. The fabric 15 as shown in the drawings is the outer side or face, and it is to be noted that on the side the bights of the stitch loops of the knitting yarns 50 and 51 occur, as do also the connecting portions between the adjacent loop stitches in each horizontal course. In the same series of wheels used to introduce the base web knitting yarn 50 for the formation of loops 52 there is also introduced upon the needles in a cooperative relation with the loops 52 a terry looping yarn 60, which is adapted to form long and prominently extending terry loops at the outside of the fabric as it is formed upon the machine, that is, the face of the fabric of Figure 15 immediately facing the observer. This terry looping yarn 60 is so arranged in the finished fabric that the cross portions 61 thereof extend closely across the outer sides of the stitch loops 52 of the base knitted web. It extends therefrom through the spaces between the stitch loops 52 to the normal inside of the base knitted web, extending about the inner side of the cross portions 63, forming part of the knitting yarn 50 and thence being turned through the spaces between the stitch loops 54 previously knitted of the knitting yarn 51, and projected to the outer side of the base knitted web H in long prominently projecting loops 67. It is thus to be noted that the terry looping yarn 60 is caught at both sides of the base web and projected to the outer side of the terry loop knitted fabric in a relation which is shown in Figure 15 and also shown in Figure 16. In the same formative operation wherein the terry loops 67 are provided upon the outer side of the fabric, a stretch preventing weft yarn 70 is applied in the fabric, which is so manipulated with respect to the knitting and terry yarns upon the needles that the same extends across the outer side of alternate stitch loops 52 of the knitting yarn 50, in unlocked relation, not being tied therewith in any manner whatsoever, extending therefrom across the outer sides of the stitch loops 54 of the knitting yarn 51, but at the inner side of the knitting yarn 50 where the latter turns at the ends of its connecting portions 63 through the knitted loops 54 of the yarn 51. This locks the weft yarn 70 at locations 72 in alternate wales near the bights of the stitch loops 54 of the knitting yarn 51, the weft yarn being so arranged that the connecting portions 61 extend across the adjacent portions of the weft

yarn 70, at the outer side of the base knitted web, as is shown in the drawings, to provide a semi-locked condition at the connecting portions of the terry yarn 60 between the loops 67 thereof, as will be apparent to anyone skilled in this art, and as is shown in Figure 15. Due to the manner in which the knitting and terry loop yarns are introduced to provide a commercial fabric, the finished product will present a very crowded arrangement of yarns immediately at the base web, quite dissimilar to the loose arrangement shown in Figures 15 and 16, which has been shown thus for purposes of clear understanding.

While the above described arrangement of terry loops 67 of the terry loop forming yarn 60 enables the terry yarn to be held fairly secure in the fabric, yet if an end forms on the fabric the same will ravel. To prevent this, it is preferred to knit in the terry loop yarn 60, on every alternate, every fourth, every fifth, every sixth, or every seventh needle. It is known that the knitting of the terry loop yarn with the knitted loops of the base web not only increases the bulk of the base web, without securing any superior results, but such knitting will result in the shortening of the terry loops in the finished product, which is a real detriment in a quality product. It must be borne in mind that terry loops of indefinite length cannot be taken care of during a knitting operation, and in the provision of a quality product while the terry loops in the finished product should be relatively long, and secured to the base web so that they shall not unravel, yet due to the limited length in which they may be projected upon the needles of the cylinder during the forming operation, a very large problem is provided. I have solved this problem by knitting in the terry loop yarn 60 with the loops 52 of the base web, upon every sixth needle in any horizontal course. This arrangement of knitting them in on every sixth needle has not been arbitrarily chosen, but has been found to best meet the practical requirements, although I do not confine myself to the knitting on every sixth needle, but may choose to knit the terry yarn upon alternate needles, or in any arrangement short of knitting the terry yarn 60 in with the base fabric on every needle. As shown in Figure 15 of the drawings the terry looping yarn 60 is knitted in with the knitting loops 52 of the knitting yarn 50 to provide knitted loops 75 shown in the drawings; these knitted loops 75 of the terry loop forming yarn following exactly the introduction of the loops 52.

The second terry loop forming yarn 80 is introduced upon the base knitted web to provide long prominently projecting terry loops 81 at the inside face of the fabric, that

is, the side of the fabric of Figure 15 facing away from the observer. This yarn 80 is so introduced that its connecting portions 83 between the loops 81, extend across the outer faces of the knitted loops 52 of the knitting yarn 50, as shown in Figure 15, quite closely and snugly thereacross, and projecting through the spaces between the stitch loops 52. The positioning and arrangement of the terry loop forming yarn 80 is simpler than for the arrangement of the terry loop forming yarn 60 above described, and it is to be noted that the connecting portions between the loops 81 are not so well locked in with the base knitted web stitches. To compensate for this I propose to knit the terry looping yarn 80 into the stitches 54 of the base knitted web, upon every third needle of the knitting machine. That is, in alternate horizontal courses the yarn 80 is knitted at 85 in with every third stitch loop 54 in that course, as shown in Figure 15. It is to be noted that these knit in loops 85 of the terry looping yarn 80 follow exactly about the stitch loops 54 of the knitting thread 51, and they project across the outer side of the stitch loops 52 and therebetween to provide the long prominently extending terry loops 81 at the inner face of the fabric. Of course, I do not restrict myself to the knitting in of the terry loop yarn 80 on every third needle, as this may be accomplished on alternate needles, or on any number of needles found to meet practical requirements.

Referring to the apparatus for controlling the yarns and fabric upon the needles, the various operating parts are shown in their relation to the needles in Figures 2 to 5 inclusive, and in the relation in which they are relatively supported upon the machine in Figure 1. Figures 2 and 3 show the relation of parts in the sequence of introducing the weft yarn 70, the stitch yarn 50 of the base web, and the terry looping yarn 60. The direction of rotation of the needles is shown by the arrows in Figures 2 and 3, and as shown to the extreme right of the needle arrangement in Figure 2, the stitch loops 54 hold the fabric K at the tops of the needles 32, with the stitch loops 54 beneath the beards of each of the needles. As the cylinder continues to rotate the fabric K comes into engagement with a fabric push down plate or foot 90, which is of course arranged at the inner periphery of the circular line of needles as shown in Figure 1, upon a suitable bracket 91 carried upon a standard 92 affixed in the back stand ring 45, shown in Figure 1. This push down foot 90 pushes the fabric down at the inside of the circular line of needles until the stitch loops 54 of the knitting yarn 51 are near the top of the cylinder C, as shown in Figure 2. With the fabric and the stitch loops 54 held in this

position, the needles 32 ride into intermeshing relation between the blades of a weft or filler yarn introducing wheel 93, which is shaped to receive the weft yarn 70 from a suitable guide 94 and position it upon the needles, pushing it downwardly in front of alternate needles and to the rear or inner sides of the remaining needles, as is shown in Figure 2. The manner in which the wheel 93 performs this operation may best be understood from Figures 8 and 12 of the drawings. In Figure 12 of the drawings is shown the bladed arrangement of the wheel 93, showing that alternate spaces 95 between the blades 96 of the wheel 93 are unobstructed, and the remaining spaces have presser lugs 97 therein. As shown in Figure 8 of the drawings, the presser lugs 97 coming into engagement with the front of alternate needles push those needles out of the normal circular alignment, as shown for the needle 32a in Figure 8, and the other needles of course ride in the spaces 95 and are not pushed out of alignment. The annular groove formed by the blades 96 receives the weft yarn 70 as shown in Figure 8, and pushes the weft yarn downwardly in front of those needles 32a which have been bent out of normal line and throw the yarn 70 back of those needles 32 which have not been bent out of line. This figure also shows the pressure foot 90 holding the fabric K, and more particularly the stitch loops 54 were anchored upon the needles 32, at the base of the needles, at the top of the cylinder C.

A clearing wheel 98, in bladed mesh with the needles 32, upon the cylinder, pushes the weft yarn 70 farther down upon the needles towards the top of the cylinder C. This clearing wheel 98 is of the usual type, and is mounted upon one of the adjustable stands 99 conventionally provided on circular knitting machines of the united needle type, being detachably and adjustably supported upon the back stand ring 45, as shown in Figure 1. At this place the fabric K is still held down upon the needles 32, preferably by means of a second push down cam or foot 100, which is shown in Figures 1 and 2 of the drawings, and which may be supported by an arm 101 carried upon a suitable stand 102 attached in the back stand ring 45. If found desirable the push down cams 90 and 100 may be of one piece.

Succeeding the lowering of the weft or filler yarn 70 upon the needles at the clearing wheel 98, the needles 32 ride into intermeshing relation between the blades of a conventional stitch wheel or burr 105, which is arranged to receive the first knitting yarn 50 of the base knitted web from a conventional guide 106 and throw the same high upon the needles 32 beneath the beards of each of said needles 32, as is shown in Figure 2 at the left hand end of the needle ar-

70

105

110

115

120

125

130

rangement, and for the major length of the needle line shown in Figure 3. It should be particularly noted that at this place the fabric K where it connects at the stitch loops 54 upon the needles 32 is still held far down on the needles near the top of the cylinder C, as is also the weft or filler yarn 70. The stitch wheel 105 together with its guide 106 may be supported upon a conventional adjustable stand 107 carried in the usual manner adjustably and detachably upon the back stand ring 45, as shown in plan in Figure 1. Succeeding the stitch wheel 105 in the direction of cylinder rotation, the fabric K rides into engagement with a push down foot or cam 110, which is of rather special construction, and adjustably and detachably supported upon a horizontal bracket arm 111, shown in Figures 1 and 6 of the drawings attached to the upper end of a standard 112, shown in Figure 6, and adjustably secured in usual manner at 113 upon the back stand ring 45. This standard or post 112 performs the second function of serving as a shaft for the sinker wheel F which introduces the first terry loop yarn 60 upon and between the needles 32.

The wheel F is of substantially the same construction as that shown in my co-pending application, Serial No. 208,483, above referred to, as improved in my U. S. Patent 1,787,010 and embodies certain improvements thereover in the relation in which the sinkers are introduced between and with respect to the needles. The wheel generally includes a rotatable wheel body 115 having a hub portion 116 bearing upon the vertical shaft or standard 112. The wheel F at its outer periphery is provided with teeth 117 intermeshing in the spaces between the needles 32 at the base of the latter near the top of the cylinder C, which gears the wheel 115 for rotation with the cylinder. On the top surface of the wheel body 115 is provided a circular or ring-shaped raised portion having exposed slots 118 therein. It is to be noted that the wheel F is arranged at the outer side of the circular line of needles. I have discovered that if instead of arranging the slots 118 radial to the axis of the shaft 112, the same are inclined slightly off the radial, so that they align, as shown in Figure 7, tangential to an imaginary circle beyond the axis of the shaft 112, at the advancing side of the rotating wheel body, the sinkers 119 may be projected more efficiently through the spaces between the needles 32 of the cylinder, for the introduction of long terry loops. Of course, as set forth in my application above mentioned, the grooves or slots 118 receive sinker or pusher members 119, the outer ends of which are kerfed to receive the terry looping yarn 60, in the case of the wheel F, and the

terry looping yarn 80 in the case of the wheel G, for the purpose of pushing the same in long loops into the spaces between adjacent needles 32 on the cylinder. Another way of describing the line in which the sinkers slide with respect to the needles 32, is that each sinker is inclined off the radial so that its projecting end first approaches and passes through an imaginary straight line intersecting the axes of rotation of the cylinder C and wheel body 115.

The sinkers 119 are of well known type, being very flat and having butts 120 facing upwardly which ride within a cam slot 121 provided in downwardly facing relation upon the cam cap 122; the latter being held stationary upon the shaft 112, by means of a set screw 123 or like expedient. A projecting cam 124 is provided to operate upon the butts 120 to project the sinkers 119 through the spaces between the needles 32; the cam 124 being resiliently controlled at 125, as mentioned in my co-pending application above referred to.

The push-down cam 110 in addition to holding the fabric K, at its stitch loop connection 54 upon the needles 32 down at the base of the needles, as shown in Figure 6, serves also as a means of supporting a yieldable resistance pad 130, which is preferably of felt; rectangular in section, and fitting closely against the needles 32 at the inside of the needle line spaced just above the top of the cylinder C so as not to interfere with the connection of the fabric K with the needles 32. This pad prevents the long loops projected through the inside of the needle line from retracting upon withdrawal of the sinkers 119, and acts to render the loops of the terry yarn taut as the needle rotates, stretching them and fixing them in position upon the needles 32, and preventing the sag and withdrawal thereof, as has been found to occur without the use of such restraining means, where the loops of the terry yarn are sufficiently long to provide the quality product desired. This felt pad has been generally described in some of my above mentioned co-pending applications, and of course the sinkers 119 project directly thereto and force the loops 67 of the terry looping yarn 60 therein, and in the case of the looping wheel G the terry loops 81 of the terry looping yarn 80 are forced into a similar pad or restraining means 132, as shown in Figure 1, and as subsequently will be mentioned.

It should be borne in mind that the pad 130 is of compressed felt, and it should be tightly held against the inside of the circular line of needles. To compensate for wear resilient means is provided to hold this pad 130 against the insides of the needle line. A preferred and simple arrangement is that of supporting the pad 130 directly upon the

convex side of the pressing cam or foot 110, being secured at one end by means of a detachable bolt or screw 135, which is countersunk at its head into the fabric 130, in the manner shown in Figure 7. This end of the pad 130 is of course rearwardly of the location where the terry looping yarn is first introduced in loops upon the needles 32 by means of the looping wheel. The bolt 135 also secures the leaf spring 136 in place at one end thereof; the leaf spring 136 being positioned between the pad 130 and the presser foot 110, and normally acting to force the pad 130 against the inside of the cylinder line to accomplish the purposes above described. The pad or restraining means 130 is of sufficient length that the loops of the terry looping yarn become set upon the needles prior to moving past the end of the pad, so that they will hold their position substantially as shown in Figure 7, after leaving the pad.

Cooperating resiliently against the upper or free ends of the needles 32 there is provided a retaining spring 140, secured at its upper end at 141 upon the outer side of the cam foot shank 110^a; the same engaging at its lower end to the rear of and near the tops of the needles 32 to brace the latter and prevent their bending during the operation of sinking the loops of the terry yarn between the needles.

It will be observed from Figure 3 of the drawings that the presser foot 110 continues a considerable distance beyond the forward end of the pad 130, in order to hold the fabric K far down at its connection with the needles 32. The terry looping yarn 60 is introduced by the sinkers of the wheel F upon the needles 32 immediately below the open ends of the beards of said needles, and thereafter, but preferably before the loops 67 of the terry looping yarn 60 leave the pad 130, the terry looping yarn 60 is operated upon by a special combination lifting and presser wheel 150, which operates to lift the connecting portions of the terry looping yarn 60 upon the shanks of the needles, to deposit some of said connecting portions beneath the beards of certain spaced needles and over the beards of the remaining needles. This wheel 150 is rotatably supported, as shown in Figure 1 of the drawings upon a suitable adjustable stand 151 secured to the back stand ring 45. In the illustration it is preferred to arrange the wheel 150 so that it will press the beards of five successive needles closed, leaving the next adjacent needle beard open, pressing the next five successive needle beards closed, and continuing the operation, and at the same time lifting the terry looping yarn 60 as it has been introduced upon the needle 32 upon the needles so that on every sixth needle whose beard has been left open, the connecting

portion will lie across the needle beneath the beard, while the connecting portions of the terry looping yarn 60 on the remaining needles are over the outer sides of the beards for a cast-off. In Figure 13 has been shown the pressing lug and bladed arrangement of the wheel 150, showing that in five successive spaces between the blades 155 there are provided pressing lugs 156, and the next succeeding single spaces 157 have been left blank. In Figure 9 is shown the manner in which the blades and pressing lugs of the wheel 150 cooperate with the needles 32; this particular view showing the pressing lug 156 holding the beard of the needle 32 closed and elevating the terry looping yarn 60 at the outside of the beard of the needle.

Succeeding the landing of the first terry looping yarn 60 with respect to the beards of the needles 32, a bladed wheel or burr 160 operates to further elevate the terry looping yarn 60 upon the needles, to immediately below the top of the beards thereof, just below the first knitting yarn 50 which is high on the needles beneath the beard of each needle. This wheel 160 is similar to an ordinary stitch wheel, and it is supported upon a conventional adjustable stand 161 carried by the back stand ring 45. The purpose of elevating the first terry looping yarn 60 is to permit the beards of the needles to be pressed closed by means of a plate presser 162, which is disposed in a plane immediately below the elevation to which the terry looping yarn 60 has been elevated upon the needles, and which closes all of the beards of the needles at a location immediately at the point where a landing wheel 164, disposed at the inside of the circular line of needles, operates to elevate the fabric where it is hung at the loops 54 upon the needles, together with the weft yarn 70. It is to be noted that the push down cam 110 terminates just prior to the time that the fabric rides into engagement with the landing wheel 164, at the location 165 shown in Figure 3 of the drawings. The landing wheel 164 is of conventional form, and its purpose of course is to lift the yarn loops as they lay upon the needles over the closed beards of the needles, above the free ends of the beards, as shown in Figure 3 of the drawings. This landing wheel 164 is supported upon a suitable adjustable bracket 164^a, which is carried inside of the circular line of needles 32 upon the grooved top plate 41, in the well known manner. A pair of cast-off wheels 167, operating at the inner periphery of the circular line of needles elevate the fabric where it is caught upon the needles, to accomplish the knitting of the stitching yarn 50 in with the fabric loops 54, and to place the weft yarn and terry looping yarn 60 in looped and knitted rela-

tion with respect to the knitting yarn 50, as has been above described, and shown in Figure 15 of the drawings along those horizontal courses illustrating the knitting loops 5 of the knitting yarn 50. It is to be observed, since the terry looping yarn 60 was introduced upon the needles above the location where the fabric K is caught upon the needles, that the terry loops 67 will be thrown 10 to the outside of the fabric as the same is knitted upon the machine, in the position in which the take-up mechanism elevates the same. This is also shown in Figure 15. The cast-off wheels 167 are supported upon 15 suitable brackets 170 carried on the grooved portion of the groove plates 41 within the circular line of knitting needles.

Referring to the cycle in which the second stitch yarn 51 of the base web is knitted, 20 and to the introduction of the second terry looping yarn 80, as shown in Figure 4 of the drawings, with the loops 52 of the stitch yarn 50 hung high beneath the beards of each of the needles, the fabric is held in a connected 25 relation at the tops of the needles, as shown in Figure 4. The terry looping yarn 80 is next introduced by means of the looping wheel G upon the needles 32 and looped through the spaces between adjacent needles 30 in exactly the same manner as that above described for the wheel F. It is to be understood that the looping wheel G is of the same construction as the wheel F, including the same types of sinkers and operating 35 mechanism, and that it introduces the second terry looping yarn 80 in the position shown in Figure 4 between the needles and upon the needles; introducing the loops into a felt pad 132 of the same nature and characteristics as the pad 130 above described. 40 For the wheel G, however, the pad 132 is carried by an arcuate bracket arm 175, supported upon a suitable standard 176 carried upon the groove portion of the plate 41 at 45 the inside of the circular line of needles. This is necessary due to the fact that the fabric is hung high upon the needles and extends therefrom to the take-up mechanism which is ordinarily above the machine. 50 However, in the case of the looping wheel F, it should be noted that the pad 130 is supported from the arm 111 which extends for its mounting to the outside of the circular line of needles, inasmuch as the fabric 55 is held down low upon the needles at that operation. The felt pad or yieldable restraining means 132 is supported as by a detachable screw 177, upon the arm 175, similar to the support of the pad 130 above 60 described, and a leaf spring 179 operates thereagainst to normally urge the pad against the needles to compensate for wear, in the position shown in Figure 1. Of course only one end of the leaf spring 179 is mounted upon the bracket arm 175, as by the screw 65

177 above mentioned. It is to be noted from Figure 4 that the terry looping yarn 80 is introduced with its long prominent loops into the pad 132 at a location below the beards of the needles. Prior to riding of 70 the loops 81 off the restraining pad 132, the terry looping yarn 80 is operated upon by a combination landing and pressing wheel 180, shown in Figure 4 of the drawings, which performs a function similar to the 75 wheel 150 above described. This wheel 180 lifts the terry looping yarn 80 upon the needles, casting some of the connecting portions between the loops over the outsides of the beards, and others beneath the beards. 80 A preferred arrangement of the wheel 180 is shown in the fragmentary developed plane portion illustrated in Figure 14 of the drawings, wherein it is shown that every third space 181 between the blades 182 is unoccupied, and the pairs of intervening spaces have presser lugs 183 therein which cooperate to press the beards of the needles closed prior to the lifting of the terry looping yarn 80 thereover, for the purpose of lifting the 90 terry looping yarn 80 to the outer sides of those beards of the needles which the presser lugs 183 engage; the terry looping yarn 80 of course being thrown beneath the open beards of those needles which pass through 95 the spaces 181, as will be quite apparent to anyone skilled in this art. It is thus apparent from Figure 4, that succeeding the wheel 180, the terry looping yarn is beneath the beard of every third needle, and the fabric 100 is hung high beneath the beard of the needle below the stitches 52. The wheel 180 is preferably supported upon an adjustable stand 185, shown in Figure 1, as mounted upon the back stand ring 45. 105

It should be remembered that the long terry loops 81 are projected to the inside of the circular line of knitting needles, and to prevent the falling of the same downwardly too far upon the needles, and to decrease the likelihood of their falling below the beards of the needles, it is preferred to provide one or more clearing wheels 190, located at the inner side of the needle line, and preferably mounted upon suitable 110 brackets 191 carried upon the groove portion of the plate 41. The number and arrangement of the clearing wheels 190 of course depends entirely upon the spaced relation between the cooperating wheels and parts on the needle line at opposite sides thereof. Their function as shown in Figure 4 consists in mainly lifting the terry looping yarn 80 high upon the needles to a 115 safe degree. 120

It should be remembered that the fabric K is still hung high upon the needles; the stitch loops 52 being caught beneath the beards thereof, and that the terry looping yarn 80 is disposed on the needles imme- 125 130

diately therebelow. As shown at the right hand end of Figure 5 a burr or wheel 200, which may consist of a usual stitch wheel, operates upon the bearded ends of the needles 32, high thereon, being rotatably supported in this position by means of an adjustable stand 201 carried on the back stand ring 45, as shown in Figure 1. The function of this wheel 200 is to throw the bight portion of the terry looping yarn 80 caught around the outer sides of the pairs of needles 32 which have been previously operated upon by the presser lug 183 of the wheel 180 over the top of the needles 32 and across the loops 52 caught on the respective needles. In cooperation with the wheel 200, an end 202 of a push down cam or foot 203 operates on the fabric to lower the same behind the needles. It is of course understood that the blades of the wheel 200 push the loops and the connecting portions of said loops into the spaces between the stitch loops 52 caught on adjacent needles, forcing them into the position shown in the finished fabric in Figure 15, at the inside face of the fabric as it is caught by the take-up mechanism and held upon the machine. It is to be noted, however, that upon every third needle the terry looping yarn 80 is caught beneath the beards, and of course the wheel 200 will not clear the terry looping yarn from these needles; its function being mainly to cast from the needles 32 the terry looping yarn 80 which is not intended to be knitted into the base web, at those needles 32 pressed by the lugs 183 as above described.

The push down cam 203 of course lowers the fabric K upon the needles, down below the beards thereof to adjacent the top edge of the cylinder C, as shown in Figure 5. In Figure 11 is shown the manner in which the blades of the wheel 200 have accomplished the purpose of throwing over the terry looping yarn 80 high upon the needles 32; the particular needle shown being one of the third needles which receives the terry looping yarn beneath the open beard thereof.

The push down cam 203 holds the fabric at the stitch loop 52 down far at the base ends of the needles, together with the terry looping yarn 80, in the relation in which it has just been applied to the fabric; it being noted that every third needle has a terry looping yarn caught thereon, as indicated by the numerals 205 in Figure 5 of the drawings.

The second knitting yarn 51 of the base web is applied upon the needles 32 in the usual manner, by means of a stitch wheel 206; the yarn 51 being applied high beneath the beards of each of the needles, with the fabric held low upon the needles by means of the push down cam 203. The latter may of course be supported by any

suitable arm or standard mechanism 207 carried adjustably upon the back stand ring 45, as shown in Figure 1, and the stitch wheel 206 may similarly be carried upon an adjustable stand 208 carried by the back stand ring 45, and supporting an ordinary yarn guide 209 from which the stitch wheel receives the stitching yarn 51 of the base web.

Subsequently the beards of the needles 32 are closed by the riding thereof against a plate or bar type of presser 211, shown in Figure 5 of the drawings, and which is positioned at the remote end of the push down cam 203. In a cooperative relation with the closing of the beards by the presser 211, a landing wheel 213, located at the inner side of the needle line, operates to lift the fabric K and the stitch loops 52 and terry looping yarn 80 caught upon the needles; all of the beards of the needles being held closed and the clearing wheel 213 lifting the yarns in the relation above described upward upon the needles and over the beards thereof, as shown in Figure 5 of the drawings. Thereafter a pair of cast-off wheels 216 operating at the inner side of the circular line of needles cast-off the stitch loops 52 and the terry yarn 80 from the needles into a knitted and received relation upon the knitting yarn 51, to form the loops 54 which are caught beneath the beards of each of the needles 32.

The presser 211 is carried by a usual type of adjustable stand 220 mounted upon the back stand ring 45, and the landing wheel 213 and clearing wheels 216 are respectively carried by suitable brackets 221 and 222 mounted on the grooved portion of the plate 41 within the circular line of needles, as shown in Figure 1 of the drawings. Thereafter the cycle of operation is repeated, starting with the arrangement shown in Figure 2.

If desired, a clearing wheel 230, shown in dot and dash lines in Figure 5, and in full lines in Figure 1, may be supported immediately forwardly in the direction of cylinder rotation with respect to the wheel 200, for the purpose of clearing yarns during the lowering at the approach end of the push down cam 203, and which also assists in preventing catching of the fabric upon the needles should a hole occur in the fabric at this location. It is supported by a conventional stand 231 carried upon the back stand ring 45.

In the example shown in Figure 15 the terry looping yarns 60 and 80 are of preferably the same weight, appreciably greater than the weight of the knitting yarns 50 and 51 of the base web H. The filler yarn 70 may or may not be as heavy as the terry looping yarns 60 and 80. To provide a quality product, the said terry looping yarns 60

and 80 must bear this relation to the base web knitting yarn.

It is within the contemplation of this invention to knit two or more terry looping yarns simultaneously upon the base web at either; or both of the wheels F and G. In practice I have found that high quality terry loop knitted fabric is provided by simultaneously knitting pairs of terry looping yarns for either or both inner and/or outer faces of the fabric. Such type of fabric has been made the subject matter of a related application, Serial No. 418,582 filed January 4, 1930.

Figure 16 shows approximately the relative length of loops of the terry looping yarns with respect to the stitch loops of the base knitted web. It is to be particularly noted that the terry loops in the finished product are each several times the length of the stitch loops of the base web.

Various changes in the shape, size, and arrangement of parts may be made to the form of invention herein shown and described, without departing from the spirit of the invention or the scope of the claims.

I claim:

1. In a knitting machine for producing terry loop knitted fabric having long prominently extending terry loops thereupon, the combination of a set of needles, means to knit a base web upon the needles, means cooperating with the needles to introduce upon the base web during its formation a terry looping yarn in long prominently projecting loops from one face of the base web, with the said terry looping yarn knitted in with certain definite relatively spaced knitted stitch loops at the base web in any course of the base in which said terry looping yarn is placed, and means cooperating with the needles to introduce upon the base web a second terry looping yarn in long prominently projecting loops from the face of the base web opposite that upon which the first mentioned terry loops are projected, with the second terry looping yarn knitted in with certain definite relatively spaced knitted stitch loops in different courses of the base web than those courses in which the first mentioned terry looping yarn is introduced and knitted.

2. In a knitting machine for producing terry loop knitted fabric having long prominently extending terry loops thereupon, the combination of a set of needles, means to knit a base web upon the needles, means cooperating with the needles to introduce upon the base web during its formation a terry looping yarn in long prominently projecting loops from one face of the base web, means cooperating with the needles and application of the terry looping yarn thereto and with the base web to knit the said terry looping yarn in with relatively spaced knitted

stitch loops of the base web in any given course in which the said terry loop is placed with a plurality of intervening stitch loops of the base web free of the knitting of the terry looping yarn therewith.

3. In a knitting machine for producing terry loop knitted fabric having long prominently extending terry loops thereupon, the combination of a set of needles, means to knit a base web upon the needles, means cooperating with the needles to introduce upon the base web during its formation a terry looping yarn in long prominently projecting loops from one face of the base web, means cooperating with the needles and application of the terry looping yarn thereto and with the base web to knit the said terry looping yarn in with relatively spaced knitted stitch loops of the base web in any given course in which the said terry loop is placed with a plurality of intervening stitch loops of the base web free of the knitting of the terry looping yarn therewith, and means cooperating with the needles to introduce upon the base web a second terry looping yarn in long prominently projecting loops from the face of the base web opposite that upon which the first mentioned terry loops are projected.

4. In a knitting machine for producing terry loop knitted fabric having long prominently extending terry loops thereupon, the combination of a set of needles, means to knit a base web upon the needles, means cooperating with the needles to introduce upon the base web during its formation a terry looping yarn in long prominently projecting loops from one face of the base web, means cooperating with the needles and application of the terry looping yarn thereto and with the base web to knit the said terry looping yarn in with relatively spaced knitted stitch loops of the base web in any given course in which the said terry loop is placed with a plurality of intervening stitch loops of the base web free of the knitting of the terry looping yarn therewith, means cooperating with the needles to introduce upon the base web a second terry looping yarn in long prominently projecting loops from the face of the base web opposite that upon which the first mentioned terry loops are projected, and means cooperating with the needles to introduce upon the base web a second terry looping yarn in long prominently projecting loops from the face of the base web opposite that upon which the first mentioned terry loops are projected, with the second terry looping yarn knitted in with certain definite relatively spaced knitted stitch loops of the base web in different courses of the base web than those courses in which the first mentioned terry looping yarn is knitted, with a plurality of intervening stitch loops of the knitting yarn therebetween free of the knitting of the second terry yarn therewith.

5. In a knitting machine for producing terry loop knitted fabric having long prom-

inently extending terry loops, the combination of a set of needles, means to knit a base web upon the needles, means cooperating with the needles and with the base web to introduce upon the base web during its formation a terry looping yarn in long prominently projecting loops from one face of the base web, the loops in length being each several times the length of each of the stitch loops of the base web, and means cooperating with the application of said terry looping yarn to the base web during the formation of the base web to knit said terry looping yarn in with only a few definite relatively spaced knitted stitch loops of the base web in any course of the base web wherein said terry looping yarn is placed.

6. In a knitting machine for producing terry loop knitted fabric having long prominently extended terry loops, the combination of a set of needles, means to knit a base web upon the needles, means cooperating with the needles and with the base web to introduce upon the base web during its formation a terry looping yarn in long prominently projecting loops from one face of the base web, the loops in length being each several times the length of each of the stitch loops of the base web, means cooperating with the application of said terry looping yarn to the base web during the formation of the base web to knit said terry looping yarn in with only a few definite relatively spaced knitted stitch loops of the base web in any course of the base web wherein said terry looping yarn is placed, and means for so placing a weft yarn upon the fabric during the knitting of the base web and introduction of the terry looping yarn that it will be considerably shorter in overall length than the overall length of either the stitch yarn or terry looping yarn in any course along which said weft yarn follows.

7. In a united needle knitting machine for producing terry loop knitted fabric having long prominently extending terry loops, the combination of a rotatable cylinder, a united needle set carried thereby, a series of wheels and devices for introducing a pair of base web forming yarns upon the needles in knitting relation thereupon, means cooperating with the needles and said pair of knitting yarns to knit a base web upon the needles, means to introduce upon the needles in cooperative formation with the base web a pair of terry looping yarns for producing long prominently projecting terry loops upon both sides of the base web as the latter is formed, and means associated with the last mentioned means for knitting the terry looping yarns in with only certain relatively spaced stitch loops of the base web during the formation of the latter.

8. In a knitting machine of the class described the combination of a rotatable cyl-

inder having a united needle set thereon of the spring beard type, means operating upon the needles to introduce and knit thereupon a base knitted web comprising horizontal courses of knitted stitch loops, means to introduce upon the needles during the formation of alternate courses of the base web a terry loop yarn for the production of long terry loops at one side of the finished fabric, said last mentioned means having means associated therewith to knit with the stitch loops of the base web the said terry loop yarn on considerably less than one-half of the total number of stitch loops of the base yarn in any course in which said terry loop yarn is introduced and knitted, and means to introduce upon the needles and produce upon the base web a second terry looping yarn having long prominently projecting terry loops at the other side of the finished fabric.

9. In a knitting machine of the class described the combination of a rotatable cylinder having a united needle set thereon of the spring beard type, means operating upon the needles to introduce and knit thereupon a base knitted web comprising horizontal courses of knitted stitch loops, means to introduce upon the needles during the formation of alternate courses of the base web a terry loop yarn for the production of long terry loops at one side of the finished fabric, said last mentioned means having means associated therewith to knit with the stitch loops of the base web the said terry loop yarn on considerably less than one-half of the total number of stitch loops of the base yarn in any course in which said terry loop yarn is introduced and knitted, means to introduce upon the needles and produce upon the base web a second terry looping yarn having long prominently projecting terry loops at the other side of the finished fabric, said second terry looping yarn being introduced in the remaining courses of the base web, and means associating with the last mentioned means for knitting in the second terry looping yarn with the stitch loops of the base web in considerably less than one-half of the total number of stitch loops in the course with which said second terry looping yarn is associated.

10. In a circular knitting machine the combination of a rotatable cylinder having a circular line of knitting needles thereon, means to introduce upon the knitting needles for the production of a unitary fabric a pair of knitting yarns, means operating upon the pair of knitting yarns upon the needles for the production of a base knitted web, means for introducing from exteriorly of the circular line of knitting needles a pair of terry looping yarns in a cooperative prominent loop projecting relation at both sides of the knitted base web with the loops of one yarn projecting at one

side of the base web only and the loops of the other yarn projecting at the opposite side of the base web only, and means associated with the last mentioned means for knitting in said respective terry looping yarns with less than one-half of the stitch loops of the base web courses in which the yarns respectively appear.

11. In combination a cylinder having a circular set of needles thereon, a base web fabric having stitch loops caught upon the needles, said needles being of the spring beard type, means to lower the stitch loops of the fabric caught upon the needles beneath the needle beards thereof, means to introduce beneath the beards of the needles a base web knitting yarn, means succeeding the introduction of the base knitting yarn to introduce a terry looping yarn from externally of the circular line of needles in long prominently projecting terry loops between the needles, and presser and cast off means to cast off from the needles the stitch loops of the base web above mentioned as positioned upon the needles together with terry looping yarn except beneath the beards of certain relatively spaced needles.

12. In combination a cylinder having a circular set of needles thereon, a base web fabric having stitch loops caught upon the needles, said needles being of the spring beard type, means to lower the stitch loops of the fabric caught upon the needles beneath the needle beards thereof, means to introduce beneath the beards of the needles a base web knitting yarn, means succeeding the introduction of the base knitting yarn to introduce a terry looping yarn from externally of the circular line of needles in long prominently projecting terry loops between the needles, presser and cast off means to cast off from the needles the knit loops of the base web above mentioned as positioned upon the needles together with terry looping yarn except beneath the beards of certain relatively spaced needles, means to introduce upon the needles at a location beneath the beards thereof and with the fabric held high upon the needles by the stitch yarn above mentioned a second terry looping yarn with long prominently projecting loops at the inner side of the circular line of needles, means to land said second terry looping yarn in the previously knitted fabric with the second terry looping yarn caught on a few relatively spaced needles beneath the beards thereof, means to introduce a second knitting yarn at a location high upon the needles above all fabric and yarns caught upon said needles, and presser, landing, and cast-off means for operating on the previously applied yarns upon the needles to knit and associate the same with the last mentioned applied stitch yarns.

13. In combination with a knitting ma-

chine needle set, sinker means for introducing a yarn upon the needles with long prominent loops projecting between the needles to the opposite side of the line of needles with respect to the sinker means, restraining means receiving and supporting the loops of said yarn from the sinker means, and resilient means normally urging said restraining means in an operative relation with said needles.

14. In knitting machine apparatus the combination of a support having a set of needles thereon, sinker means for introducing a yarn upon the needles with loops projecting through the spaces between the needles to the opposite side of the line of needles from the location of the sinker means, a yieldable restraining pad at said side of the line of needles, means to normally hold and support said pad in position for receiving and restraining the loops of said yarns, and resilient means cooperating between the last mentioned means and pad and resiliently urging the pad in the direction of said needles and thereagainst.

15. In knitting machinery the combination of a circular rotary cylinder having a circular set of relatively spaced needles thereon, a sinker wheel rotatably supported at the outer peripheral line of said circular set of needles, said sinker wheel having non-radial slots therein sloping off radial relation with either the axes of rotation of the cylinder or wheel so that the outer ends of said slots first intersect a straight line intersecting the axes of rotation of the wheel and cylinder during rotation, sinkers slidably in said slots, and means operating on the sinkers to introduce them in the spaces between the needles for the introduction of yarn in loops between the needles and thereupon.

16. In knitting machinery the combination of a rotary cylinder, a united needle set on the rotary cylinder, a fabric lowering cam for lowering the fabric caught upon the needles to the lower parts of said needles, a succeeding weft yarn introducing wheel having means for introducing the weft yarn to the fore part of alternate needles and the backs of the remaining needles, a stitch wheel for introducing a knitting yarn beneath the beards of the needles at a location above the fabric caught upon the needles and the weft introducing yarn, a sinker wheel succeeding said stitch yarn introducing wheel for introducing a terry looping yarn upon the needles below the previously applied knitting yarn but above the weft yarn and fabric caught upon the needles, means for landing upon the beards of said needles the terry looping yarn as applied to the needles with the terry looping yarn caught by a few certain relatively spaced needles, and presser, landing and cast off means for discharging all of said yarns

caught upon the needle except the stitch yarn introduced upon the needles as previously mentioned.

17. In a circular knitting machine the combination of a rotary cylinder having a united set of spring beard needles in circular arrangement thereon, means at the inside of the circular line of needles for lowering fabric held upon the needles low down upon the needles below the spring beards thereof, means for introducing from externally of the circular line of knitting needles while the fabric is thus held down upon the needles a first base web forming stitch yarn, means for introducing upon the needles while the fabric is thus held down upon the needles a terry looping yarn from externally of the circular line of needles at a location below the applied location of the first stitch yarn, with the terry yarn looping to the inside of the circular line of needles between the needles in long prominently extending loops, and means for elevating the fabric caught upon the needles, for pressing the beards of the needles and landing and casting off the yarn in a knitted and introduced relation upon the first stitch yarn with the loops of the terry yarn projected to the outside of the fabric as held upon the machine; means for introducing upon the needles from externally of the circular line of needles a second terry yarn in long prominently projecting loops at the inner side of the circular line of needles at a location below the location at which the fabric is held on the needles by the loops of the above mentioned first knitting yarn, means for elevating said second terry looping yarn upon the needles beneath the beards of a few spaced needles and casting it over the tops to the rear of the remaining needles, means to lower the fabric upon the needles with the second terry looping yarn in the relation first mentioned with the terry loops of the second terry looping yarn projecting to the normal inside of the fabric caught upon the needles, means to introduce a second stitch yarn beneath the needles beards at a location above where the fabric is caught upon the needles, and means for casting off the fabric as caught upon the needles together with the portions of the second terry looping yarn caught upon the needles onto the second stitch yarn.
18. In a knitting machine the combination of a rotatable cylinder having a united set of spring beard needles thereon with fabric held by stitch loops thereon, means for introducing upon the needles from externally of the circular line of needles a terry yarn in long prominently projecting loops at the inner side of the circular line of needles at a location below the location at which the fabric is held on the needles, means for elevating said terry looping yarn upon the needles beneath the beards of a

few spaced needles and casting it over the tops to the rear of the remaining needles, means to lower the fabric upon the needles with the terry looping yarn in the relation mentioned with the terry loops of the terry looping yarn projecting to the normal inside of the fabric caught upon the needles, means to introduce a stitch yarn upon the needles at a location above where the fabric is caught upon the needles, means for casting off the fabric as caught upon the needles together with the portions of the terry looping yarn caught upon the needles onto the last mentioned stitch yarn.
